UNITED STATES PATENT OFFICE.

GEORGE WILLIAM HIZER, OF DETROIT, MICHIGAN.

REMOVABLE CEILING FOR ENAMELING-OVENs.

1,037,910.

Specification of Letters Patent. Patented Sept. 10, 1912.

Application filed October 2, 1911. Serial No. 652,338.

To all whom it may concern:

Be it known that I, GEORGE W. HIZER, a citizen of the United States, and a resident of Detroit, in the county of Wayne and 5 State of Michigan, have invented a new and useful Removable Ceiling for Enameling-Ovens, of which the following is a specification.

This invention relates to means for preventing flakes or small granules of soot or other undesirable materials from falling from the ceilings of enameling ovens onto the wet enamel coating of sheet metal, and its object is to provide a removable false 15 ceiling for such ovens, which ceiling can be easily and thoroughly cleaned when desired.

In the accompanying drawings Figure 1 is a perspective view of an enameling oven. Fig. 2 is a transverse section, and Fig. 3 20 is a longitudinal section of the same. Fig. 4 is a detail of a small hanger which may be employed in this oven.

Similar reference characters refer to like parts throughout the several views.

25 The enamel on mud-guards, hoods, and bodies of automobiles, and of other high-class sheet metal work, is baked onto the metal in ovens which are heated to a temperature of from 250 to 350 degrees Fahrenheit. This heating is done, as a rule, by means of gas flames, and because of imperfect combustion, a certain amount of lamp-black or soot is formed. This lamp-black or soot seems to unite with the vapors of the 30 solvent of the enamel and attaches itself to the walls and ceiling of the oven. After several months, small particles of this material detach themselves from the ceiling and fall onto the soft enamel of the goods 35 within the oven. The result is that specks, warts, and blisters are formed on the enamel, often necessitating the entire removal of the enamel by means of a hot acid bath.

40 It is customary to periodically clean the ceiling and the supporting bars by means of wire brushes and thorough scrubbing, but for some reason not understood, a perfect rain of such particles falls during the first 45 and often second baking following such cleaning. The probability is, that these fine particles are pushed into the cracks and between overlapping plates which form the ceiling, during the cleaning, and are then 50 released during the baking because of the

expansion and other movement of the ceiling plates due to the great increase in temperature. Whatever be the reason, it is the universal experience of those skilled in this art, that the enamel of substantially the entire batch of the articles being enameled at the first baking following a cleaning of the oven, is imperfect, and it is also the universal experience that a very large proportion of such articles must be reenameled. 60 65

The invention set forth in this application is embodied in a false or removable ceiling which can be absolutely cleaned. The preferred form is a series of sheet metal plates overlapping at edges and ends, and of such 70 length that they can be easily taken out of the oven and put into a hot bath of weak acid, which removes every trace of the soot and other undesirable materials.

The oven shown in the accompanying 75 drawing has a top 1, sides 2, bottom 3, front 4, back 5 and doors 6 of any desired material and construction. The heating gas is conducted into the oven by means of pipes 7 and escapes through the small holes 8 shown 80 in Fig. 1. The flow may be controlled by valve 9. Extending across between the walls 2 are supporting members 10, preferably I-beams, upon which rest a series of metal plates 11 having upturned edges 12, and the 85 second series of plates 13 having down-turned edges 14. These plates may be of any desired length, and overlap, the outer ends of the end plates preferably resting on channels 15 secured to the back 5 and the 90 front 4 of the oven. Small stirrups 16 may carry the bars 17, and the hooks 18 hang over these bars 17 and support the pieces 19 of work, mud-guards being shown. As these stirrups 16 are easily removable, the 95 bars 17, which may be also formed of short lengths, can also be taken down and placed in the acid bath. The I-beams 10 may then be brushed and if desired washed with weak acid. 100

It has been found that in ovens provided with false ceilings such as shown in the drawing, the consumption of gas is much less than in those not so provided, owing to the fact that a dead air space is formed between the top of the oven and the sheet metal ceiling, which space substantially prevents the radiation of the heat upward. The plates 11 and 13 will be cleaned as often as necessary to prevent too great an accu- 110

mulation of soot, and thus the danger of spoiling the enamel being baked will be avoided.

The invention is not limited to the use of sheet metal plates having downturned edges such as shown in the drawings, nor in connection with I-beams 10, for the plates may be of any desired shape and size and the supporting beams may be of any cross section.

10 Having now explained my construction, what I claim as my invention and desire to secure by Letters Patent is:

15 In an enameling oven, the combination with the sides and top of the oven, of a series of beams extending across the oven and

spaced from the top, a series of removable of stirrups depending from said beams, and having overlapping edges and ends, a series of stirrups depending from said beams, and a series of removable bars carried by said 20 stirrups, said bars adapted to receive the supporting hooks of the metal articles being enameled.

In testimony whereof, I have signed this application in the presence of two subscribing witnesses.

GEORGE WILLIAM HIZER.
